(57) CLAIM

I claim the ornamental design for a set of locking members, as shown.

DESCRIPTION

FIG. 1 is a perspective view of a first locking member in a first direction, shown separately for ease of illustration; FIG. 2 is a perspective view of the locking member of FIG. 1 as viewed in a second opposite direction; FIG. 3 is a side view of the locking member of FIGS. 1 and 2;

FIG. 4 is a perspective view of a second locking member in a first direction, shown separately for ease of illustration; FIG. 5 is a perspective view of the locking member of FIG. 4 as viewed in a second opposite direction; and, FIG. 6 is a side view of the locking member of FIGS. 4 and 5.
